UNITED STATES PATENT OFFICE

94,052

DESIGN FOR A COMBINED LAMP BRACKET AND PENDANT

Emory W. Sadler, Philadelphia, Daniel N. Pierce,
Glenside, and Martin P. Mortensen, Philadelphia,
Pa., assignors to Fox Company, Philadelphia,
Pa., a corporation of Pennsylvania

Application February 24, 1934, Serial No. 50,845

Term of patent 7 years

To all whom it may concern:

Be it known that we, Emory W. Sadler, Daniel N. Pierce, and Martin P. Mortensen, citizens of the United States, residing, respectively, in Philadelphia, county of Philadelphia, and State of Pennsylvania, in Glenside, county of Montgomery, and State of Pennsylvania, and in Philadelphia, county of Philadelphia, and State of Pennsylvania, have invented a new, original, and ornamental Design for a Combined Lamp Bracket and Pendant, of which the following is a specification, reference being had to the accompanying drawing, forming part thereof.

Figure 1 is a side elevation of a combined lamp bracket and pendant, showing our design.

Figure 2 is a rear elevation of the combined lamp bracket and pendant, shown in Figure 1.

Figure 3 is a top plan of the combined lamp bracket and pendant, shown in Figures 1 and 2.

We claim:

The ornamental design for a combined lamp bracket and pendant as shown.

EMORY W. SADLER.
DANIEL N. PIERCE.
MARTIN P. MORTENSEN.
